(57) **CLAIM**

The ornamental design for a docking station for tablet computer, as shown and described.

DESCRIPTION

FIG. 1 is a perspective view of a docking station for tablet computer showing my new design in an open state; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a perspective view thereof in a closed state with the handle pulled out; FIG. 9 is a rear view thereof in a closed state with the handle pushed in; and, FIG. 10 is a perspective view thereof in an open state with a tablet computer mounted.

The broken line showing of the tablet computer in FIG. 10 represent unclaimed environment and form no part thereof. The broken line showing of portions of the docking station for tablet computer in the drawings represent unclaimed portions of the claimed design and form no part thereof.
